UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

MEANS AND METHOD FOR TRIMMING BLANKS.

Application filed December 12, 1924. Serial No. 755,523.

This invention relates to means and method by which a blank may be given a polygonal cross-section, such as the square, hexagonal or octagonal shapes of bolt heads, nuts and the like, or a many sided shape 5 of any kind, such, for instance, as a circular section with flat sides as on shackle bolts, or the like. By "polygonal" I mean any such shape.

10 It is the object of this invention, among other things, to give a trimmed cross section to a blank by cutting the metal with the minimum amount of cutting pressure and with cuts that produce different cross 15 sectional areas at different points of the blank, and then planishing the blank so as to provide clean, smooth, finished, unbroken surfaces, of a uniform level.

As the trimming of bolt heads, nuts or 20 the like, has been heretofore carried out, the blank is forced through the cutting die by a plurality of punches of varying diameters, and the cut surfaces of the blank being of uniform cross sectional area 25 throughout the length of the cut surface.

The breaking or tearing of the metal by the cutting operation is at the end of the cut at one end of the blank.

I have found that in trimming blanks a 30 very superior product may be produced by using two cutting dies, one of which does the major portion of the cutting and brings the excess metal or flash near the top of the head and the cut of the other die being of a less cross sectional area and extends only 35 a limited distance from the end of the blank. This limits the cut of the first mentioned die and any tearing or breaking of the stock is at a point distant from and not at the 40 end of the blank. This undercut made by the last mentioned die provides a relief for the drawing of the stock on the cut surface as it passes through the planishing die.

In the drawings:—

45 Figure 1 is a sectional view of the dies and adjacent parts in the relative positions occupied by them when the cutting dies have partly trimmed the blank;

Figure 2 is a face view of one of the dies; Figure 3 is a view of the parts similar to 50 that shown in Figure 1 with the cutting dies closer together and the operation at a more advanced stage;

Figure 4 is a view of the parts similar to 55 that shown in Figure 1, illustrating their relative positions after the blank has passed the cutting edges of the dies and is being advanced toward the planishing die;

Figure 5 is a view of the parts, similar to that shown in Figure 4, but with the 60 blank passing through the planishing die;

Figure 6 is a side and end elevation respectively of the blank as presented to the dies;

Figure 7 is a side and end elevation 65 respectively of the head portion of a blank as produced by the tools when in the relative positions occupied by them, as disclosed in Figure 1;

Figure 8 is a side and end elevation 70 respectively of the head portion of a blank as produced by the tools when in the relative positions occupied by them as disclosed in Figure 3;

Figure 9 is a side and end elevation 75 respectively of the head portion of a blank after it has passed the cutting edges of the dies, substantially as shown in Figure 4; and

Figure 10 is a side and end elevation 80 respectively of the head portion of a blank after it has passed the planishing die, substantially as shown in Figure 5.

In the embodiment of this invention, I 85 provide a fixed die 10, which is shown herein as having an hexagonal opening 11 therethrough, and supported adjacent thereto and in rear thereof is the planishing die 12. The die 10 is shown as having a face 13 that recedes slightly from the cutting edge 90 14 thereof but may be flat if desired.

In the abutting faces of each of the dies 10 and 12 are radial slots 15, which register with each other when the dies are assembled 95 and provide a passage for a stream of cutting compound into the opening of the dies

for the purpose of lubricating the faces of the planishing die and to wash therethrough such chips, if any, as may enter the trimming die. While I have shown the dies 10 and

5 12 as being separate, they may be made a single die, and the opening produced by the slots 15 may be provided in one of the dies instead of both, as shown.

10 A die 16 is mounted so as to be moved toward and away from the fixed die 10, and independently movable therein is a pusher rod 17, which is partially supported by a bushing 18.

15 Through the end of the die 16 is a hexagonal opening 19 slightly smaller than the opening 11 and through which is movable the outer end of the pusher rod 17.

20 While I have shown the hexagonal openings 11 and 19 through the dies 10 and 16 respectively, it is obvious that openings of other shapes may be provided if desired, the shape depending upon the shape of the head of the finished blank.

25 The outer end of the pusher rod 17 is herein shown as being concaved at 20 to conform to the face of the end of the blank. It may, however, be flat or any other shape.

30 Movable mounted within the openings in the dies 10 and 12 is the quill 21, the bore of which is substantially the same as that of the shank of the blank, which is supported therein.

35 In practice, it is usual to have the die 10 held stationary and the die 16 movable toward and away therefrom, but this is not essential, as both dies may move or the die 16 remain stationary and the die 10 be moved in relation thereto. In either case at the beginning of the operation the dies are 40 a sufficient distance apart to permit the placing therebetween of a blank 22 and as the die 12 then moves toward the die 10, the shank of the blank enters the quill 21, which supports and accurately centers it 45 in relation to the openings 11 and 19. During the forward movement of the die 16 the concaved end 20 of the pusher rod 17 is slightly in rear of the cutting edge 23 of the die 16 and the head of the 50 blank, which is usually circular in cross section before the beginning of the operation is shaved by the dies 10 and 16. The length of the cut on the blank by the die 16 is determined by the relative position of 55 the end of the pusher rod 17 to the cutting edge 23. In practice the length of this cut is short compared to the length of the cut of the die 10, a fair illustration of the length of these relative cuts being shown in Figure 3.

60 The metal accumulated by the cutting operations is folded back over the angular faces 13 and 24 of the dies 10 and 16 respectively, the space therebetween increasing 65 in width outwardly from the openings 11

and 19. Thus the surplus metal has ample space within which to free itself without interfering with the cutting operations.

66 In Figure 1 the tools and the blank are shown in the relative positions occupied by them when the blank is partly trimmed, while in Figure 3 with the dies in the position when nearest to each other. In this latter figure the die 16 has come to a full stop but the pusher rod 17 continues its movement and forces the blank through the die 10 and beyond the cutting edge 14, the blank and the parts in their then positions being shown in Figure 4, and in Figure 5 the blank is shown as being passed through the planishing die 12.

70 A view of the blank after it has passed the cutting edge 14 of the die 10 is shown in Figure 9, wherein it will be noted that the tear of the metal at the end of the cutting stroke is between the lines "a" and "b" 75 and not at the end of the blank, this being due to the fact that the cross sectional cut near the head of the blank made by the die 16 is of less cross sectional area than that 80 made by the die 10. Thus there is no breaking or tearing of the metal at the end of the blank. Thereafter, as the head of the blank passes through the planishing die the metal 85 on the cut face thereof is drawn into the relief on the head between lines "a" and "b", filling out the same and providing a smooth 90 surface and eliminating any possibility of breaking off of the metal at the junction of the cut faces with the end of the blank. 95

100 What I claim as new and desire to secure by Letters Patent, is:—

1. The method of giving a trimmed cross section to a blank, consisting of cutting the blank from opposite ends thereof, the cut 105 from the top of the blank being deeper than the cut from the bottom of the blank, and the surplus metal accumulated at the junction of the two cuts removed while the blank is passing through the cutting tools, and then 110 by planishing or the like, iron out the cut surfaces so that they are smooth and at all points throughout their length equally distant from the axis of the blank.

2. The method of giving a trimmed cross 115 section to a blank, consisting of cutting the blank from opposite ends thereof, the cut from one end being deeper than the cut from the other end and the cut surfaces thereafter made of a uniform level by planishing or the like, by a movement through planishing tools that first engage the cut surface from which the thinnest cut has been taken.

3. In mechanism of the class described; 125 a pair of oppositely disposed dies, each having an opening therethrough with cutting edges around the opening, the opening in one of the dies being of less area than the opening in the other die, said dies being 130

movable relative to each other and cutting the beginning of the cutting operation and the blank from opposite ends thereof; and maintaining such position during the cutting action of the die adjacent thereto. In testimony whereof, I have hereunto affixed my signature.

10

RICHARD LESTER WILCOX.
